CEILING-SUSPENDED SPEAKER CABINET

Alfred J. Erickson, 928 S. Hampstead, Anaheim, Calif.

Filed Oct. 25, 1962, Ser. No. 72,268

Term of patent 14 years

(Cl. D26—14)

FIGURE 1 is a perspective view to an enlarged scale of a ceiling-suspended speaker cabinet, showing one form of my new design wherein the base of the dome is round and the surface of the dome is substantially hemispherical; and

FIGURE 2 is a side elevational view to a reduced scale of the form shown in FIGURE 1;

FIGURE 3 is a bottom plan view to a reduced scale of the form shown in FIGURE 1;

FIGURE 4 is a side elevational view of a ceiling-suspended speaker cabinet, showing another form of my new design wherein the base of the dome is octagonal rather than round and the surface of the dome is subdivided into eight uniform areas, each bearing a circular vent; and

FIGURE 5 is a bottom plan view of the form shown in FIGURE 4.

The top, not shown, is a plain flat surface.

The dominant features of the design reside in the portions shown in full lines.

I claim:

The ornamental design for a ceiling-suspended speaker cabinet, substantially as shown and described.
